[57] CLAIM

The ornamental design for a table, as shown and described.

DESCRIPTION

FIG. 1 is a top view showing my new table design;
FIG. 2 is a side view thereof which is the same on the
there remaining sides;

FIG. 3 is a bottom view thereof;

FIG. 4 is a top view of a table, showing a second em-
bodiment of my new design;

FIG. 5 is a vertical cross-section taken along line 5—5
of FIG. 1;

FIG. 6 is a vertical cross-section taken along line 6—6
of FIG. 4;

FIG. 7 is a perspective view of the table shown in
FIGS. 1 and 2.

FIG. 1
